MINING MACHINE

Joseph F. Joy, Claremont, N. H., assignor to Sullivan Machinery Company, a corporation of Massachusetts

Application November 12, 1934, Serial No. 752,671

34 Claims. (Cl. 262—28)

This invention relates to mining machines, and more particularly to improvements in coal mining machines adapted to cut relatively narrow slots in a coal seam.

5 An object of this invention is to provide an improved coal mining machine. Another object is to provide an improved coal mining machine which is capable of being maneuvered with facility, and having improved coal cutting devices 10 adjustable to cut either vertical or horizontal slots in a rapid and efficient manner. A further object is to provide an improved coal mining machine arranged to slide over the mine floor and having improved flexible feeding means. 15 Another object is to provide in a coal mining machine of the above character, improved means for swinging the cutter blade and for adjusting the cutter blade about a longitudinal axis to move the blade into either horizontal or vertical cutting positions. Yet another object is 20 to provide an improved coal mining machine, the major movements of which are hydraulically effected and having embodied therein an improved hydraulic system for operating and controlling said hydraulic devices. Yet another object is to provide an improved "walking" jack arrangement whereby the machine may be read- 25 advanced with a "walking" action, the weight of the machine being substantially balanced by a careful arrangement of the parts, thereby facil- 30 itating the function of "walking". Yet another object is to provide improved positioning and locking means for the cutter blade. Another object is to provide improved drive and control 35 means for, and an improved arrangement of the flexible feeding element engaging feeding mem- bers of, the flexible feeding means for the machine. These and other objects and advantages of the invention will, however, hereinafter 40 more fully appear.

In the accompanying drawings there is shown for purposes of illustration one form which the invention may assume in practice.

In these drawings,—

45 Fig. 1 is a plan view of the illustrative embodiment of the improved coal mining machine, the top horizontal cutting position of the cutter blade being indicated in dotted lines.

50 Fig. 2 is a side elevational view of the machine shown in Fig. 1, the horizontal top cutting position of the cutter blade being indicated in dotted lines.

55 Fig. 3 is an enlarged longitudinal sectional view taken substantially on line 3—3 of Fig. 1.

Fig. 4 is a fragmentary plan view of the cutter head and its associated mechanism.

55 Fig. 5 is a horizontal sectional view taken substantially on line 5—5 of Fig. 3.

60 Fig. 6 is an enlarged cross sectional view taken

on line 6—6 of Fig. 2, the elevated position of the machine being indicated in dotted lines.

Fig. 7 is a central longitudinal section through one of the longitudinal feed cylinder devices.

Fig. 8 is an enlarged vertical sectional view taken on line 8—8 of Fig. 1.

Fig. 9 is a detail sectional view taken substantially on line 9—9 of Fig. 6.

Fig. 10 is a cross sectional view taken substantially on line 10—10 of Fig. 3.

Fig. 11 is a plan view of the sub-frame or skid plate and the main base in position thereon.

Fig. 12 is a diagrammatic elevational view showing, with parts shown in longitudinal section, the action of the "walking" jack in advancing the sub-frame or skid plate relative to the main base.

Fig. 13 is a diagrammatic view showing the hydraulic system.

Fig. 14 is a diagrammatic view showing the machine cutting a horizontal slot in the coal face in accordance with the room and pillar system.

Fig. 15 is a diagrammatic view showing the machine operating as a floor type, shear cutter.

In this illustrative embodiment of the invention there is shown a coal mining machine of the flexibly fed, floor type generally comprising a sub-frame or skid plate 1 having a smooth bottom surface 2 adapted to rest upon and slide in any direction over the mine floor. Mounted on the skid plate 1 for longitudinal rectilinear movement with respect thereto is a main frame or base 3, mounted on the forward end of which, for rotation about an axis extending longitudinally of the main base, is a cutter head 4 carrying a pivoted kerf cutter herein in the form of a cutter blade or bar 5 having an endless cutter chain 6 mounted on its margin for circulation thereabout. Flexible feeding means is employed for feeding the machine bodily over the mine floor both during maneuvering of the machine and the cutting operations and herein comprises relatively rotatable feeding members, herein in the form of haulage drums 7 and 8, arranged on horizontal aligned axes extending transversely of the machine, and each adapted to cooperate with a flexible feeding element herein in the form of wire ropes or cables 9 and 10, respectively. A motor 11 mounted on the main base 3 constitutes the sole prime mover for the various mechanisms of the machine, and improved devices are employed, driven by this motor, for driving the feeding drums and for operating the cutter blade swinging means, for driving the cutter blade, for moving the main base rectilinearly with respect to the skid plate and for effecting the "walking" function of the machine, as will hereinafter be described.

The sub-frame or skid plate 1 runs substantially the entire length of the machine, and as above

60

pointed out, this skid plate has rectilinearly guided thereon the main base 3 on which is mounted all the principal mechanisms of the machine, including the flexible feeding and cutting mechanisms. Arranged longitudinally along each side of the main base 3 and secured thereto, as by bolts, are supporting girders 13, 13 (see Fig. 6), and these in turn are supported by lower guide rails 14, 14 secured as by welding to the 10 girders 13. Beneath the rails 14 and slidably relatively thereto is the sub-frame or skid plate 1, and extending the length of this skid plate, adjacent to the base rails 14, are guiding girders 15, 15, while cooperating therewith are retaining bars 16, the elements 15 and 16 being secured to the skid plate as by riveting, and these elements cooperating to form longitudinal guideways 17, 17 in which the guide rails 14 are slidably guided. By this arrangement, the main 20 base 3 is slidable on the skid plate 1, this being accomplished by a pair of hydraulic power devices 19, 19, one arranged at each side of the main base (see Fig. 6) between the sides of the latter and the upstanding side flanges 20 25 of the skid plate 1 and in adjacency to the supporting girders 13. These devices each include a hydraulic cylinder 21 having its rear head secured to the adjacent side of the main base and containing a reciprocable piston 22 having a 30 forwardly extending piston rod 23 fixed at its forward end at 24 to the forward end of the skid plate 1, as clearly shown in Figs. 3 and 11. It will thus be seen that when hydraulic pressure is supplied to the cylinders 21 the main base 3 and 35 the skid plate 1 will be reciprocated relative to one another, as shown by the dotted lines in Fig. 12.

Now referring to the improved "walking" jack arrangement for the machine, it will be noted 40 that arranged midway between the sides of the main base substantially at the center of gravity of the machine is a "walking" jack cylinder 25 containing a reciprocable jack piston 26 having a piston rod or plunger 27 in the form of a jack element extending through the packed lower head 28 of the cylinder 25. As clearly shown in Fig. 11, the skid plate 1 is provided with a centrally located longitudinal slot 29 and has its forward portion cut away at 30, and the jack piston 27 is adapted to project down through 45 this slot 29 into engagement with the mine floor. When hydraulic pressure is admitted to the upper end of the cylinder 25, the piston will be forced downward, causing the end of the piston rod 27 50 to engage the mine floor, as shown in dotted lines in Fig. 6, and upon the continued supply of pressure to the cylinder the jack piston will raise the entire machine off the mine floor except for a slight contact at one end. If now hydraulic pressure is admitted to the rearward ends of the 55 longitudinal feed cylinders 21, the sub-frame or skid plate 1 will be projected forwardly beneath the main base 3 (Figs. 11 and 12). If the hydraulic pressure is then released from the 60 "walking" jack cylinder, the piston rod thereof will be forced upward and the skid plate 1 with the machine on it will again rest on the mine floor in relatively extended position. If hydraulic pressure is now admitted to the forward ends 65 of the longitudinal feed cylinders 21, the main base 3 will be advanced along the skid plate 1 until the two are again in fully superimposed position. The operation can be repeated by again forcing hydraulic pressure into the "walking" 70 jack cylinder whereby the machine is again

substantially raised off the mine floor, the skid plate again extended, the machine then brought to rest on the mine floor as before, and the main base again brought forward into coincidence with the skid plate. In this way the machine may be advanced rapidly with its own self-contained mechanism by a "walking" action or "caterpillar-like" motion. 5

Now referring to the improved coal cutting devices, it will be noted that the cutter head 4 10 has a cylindrical bearing portion 32 journaled in a bearing sleeve 33 supported within a cylindrical neck frame 34, herein formed integral with the forward portion of the main base frame 3, and formed integral with the head frame is a 15 radial flange 35 having bolted thereto a worm wheel 36. This worm wheel is provided with an annular groove 37 receiving a radial flange 38 formed on the cylindrical bearing portion 34 and the worm wheel having an inwardly directed flange 39 overlying the rear face of the flange 38 for retaining the cutter head on the bearing portion 34. Journaled in a bracket 40 suitably secured to the bearing portion 34 for the cutter head is a worm 41 meshing with the worm 25 wheel 36, and this worm is fixed to a transverse shaft 42 adapted to be rotated in any suitable manner, as by a suitable turning instrument connectible to the squared end 43 of the shaft (see Fig. 2). It will thus be seen that the cutter head may be manually rotated through the worm gearing 36, 41 into either a vertical or horizontal cutting position about a horizontal axis extending longitudinally of the machine. The worm gearing is of the self-locking type and locks automatically the cutter head in adjusted 30 position about the head axis. The driving connections between the cutter chain 6 and the motor 11 comprise a horizontal, longitudinally, extending shaft 45 connected by a coupling 46 to the power shaft 47 of the motor 11. As shown in Fig. 3, the shaft 45 is suitably journaled within the main base and has splined thereto at its forward end at 48 a clutch member 49 connectible to a clutch member 50 keyed to the rear end of a shaft 51. This shaft is arranged with its axis coincident with the cutter head axis and aligned with the shaft 45, and is suitably journaled within bearings supported within the cutter head frame. Fixed to the forward end of the shaft 51 is a bevel gear 52 meshing with a large bevel gear 53 connected by a multiple disc clutch 54, of a well known design, to a shaft 55. As illustrated, the shaft 55 is suitably journaled in the cutter head frame and is arranged with its axis at right angles and perpendicular to the axial line of the cutter head 4. Secured to the outer end of this shaft is a chain sprocket 56 which engages and drives the cutter chain 6 for effecting orbital movement of the latter about 40 the margin of the cutter blade 5. The clutch 49 is operated by a shifter member 57 having lever operating means provided with a pivoted operating handle 58 (see Fig. 1). The clutch 49, 50 constitutes the main cutter drive clutch, 45 and when connected the cutter chain may be driven by the motor 11 through the coupling 46, shaft 45, bevel gearing 52, 53 and the sprocket drive shaft 55. The cutter blade 5 is of an elongated, relatively thin design, and is mounted for longitudinal adjustment toward and from the cutter chain drive sprocket 56 in a guideway 60 formed in a cutter hanger 61. The cutter blade is swingably mounted about an axis coincident with the cutter drive sprocket axis, and the 70 75

hanger 61 is provided with a bearing hub 62 journaled on bearing sleeves 63 supported by a hub 64 formed integral with the cutter head frame, the hanger being retained in position on the bearing hub by a retaining plate 65 secured to the hub, this plate also forming a bearing retainer for the cutter chain drive sprocket hub bearing. The hanger 61 is provided with a projection 66 in which is rotatably mounted a rotating member 67 having a screw 68 threaded within the rear portion of the cutter blade. It will be evident that when the screw is rotated, the cutter blade may move inwardly or be moved outwardly within its guideway 69 on the hanger frame 61 to vary the tightness of the cutter chain. A lock nut 69 is provided for locking the adjusting means in its adjusted position.

The means for locking the cutter blade in its different positions about its pivotal axis with respect to the cutter head frame comprises a lock member or latch 70 pivoted at 71 on the hanger frame 61 and having an operating handle 72, and this locking member is receivable in radially located locking recesses 73 formed in a flange 74 integral with the cutter head frame. A spring pressed plunger 75 mounted on the locking member 70 and engageable with the hanger frame urges the member 70 into its locking position. As shown in Fig. 4 there is guided in a bore 76 formed in the hanger frame 61 a plunger 77 normally urged inwardly by a coil spring 78 and having an operating handle 79. When the locking latch 70 is swung outwardly into its released position, the locking plunger 77 is adapted to move in back of the member 70, thereby to hold it out in its released position. Thus by moving the latch 70 the cutter blade support 61 may be swung angularly and the latch dropped into the latch slot 73 next to the desired position.

The improved mechanism for swinging the cutter blade about its pivotal axis with respect to the cutter head comprises a hydraulic cylinder 80 secured to the side of the main base 3 and containing a reciprocable piston 81 having a forwardly projecting piston rod 82. The forward end of this piston rod is connected by a pin and slot connection 83 to a lever 84 keyed to one end of a shaft 85 herein extending transversely across the top of the main base and suitably journaled thereon. Also keyed to the shaft 85 adjacent the opposite ends thereof near the opposite sides of the machine are cranks 86 and 87 having pivotally connected thereto links 88, 89, respectively (see Figs. 4 and 10). The cutter blade hanger frame 61 has formed integral therewith perforated ears or lugs 90 and 91, and when the cutter head is in the position shown in Figs. 1 and 2, the link 89 is connected to the lug 90 and when hydraulic pressure is supplied to the cylinder 80 the piston 81 is moved axially within its cylinder, thereby swinging the lever 82, rotating shaft 85, swinging the lever 87 and through the link 89 and lug 90 swinging the cutter blade about its pivot. When the cutter blade is rotated to the opposite side of the axis of the cutter head the link 88 is connected to the lug 91 to effect swinging of the cutter blade with respect to the head. It will thus be seen that the cutter blade may be swung about its pivot in either of two predetermined vertical cutting positions at opposite sides of the cutter head axis.

Now referring to the improved flexible feeding means including the feeding drums 7 and 8, and more particularly to the driving means for the latter, it will be noted that keyed to the longi-

tudinal cutter chain drive shaft 45 is a spur pinion 95 (see Fig. 3) meshing with a spur gear 96 keyed to a shaft 97 herein arranged parallel with and below the shaft 45 and likewise suitably journaled in the frame of the main base. Keyed to the shaft 97 is a high speed gear 98 and a low speed pinion 99, the high speed gear meshing with spur gears 100, 101 (see Fig. 5) connectible by multiple disc clutches 102 and 103 of a usual design to longitudinally extending shafts 104 and 105 herein arranged parallel with the shaft 97 at opposite sides thereof and equidistantly spaced therefrom. The slow speed pinion 99 meshes with gears 106 and 107 connectible by multiple disc clutches 108 and 109 to the shafts 104 and 105, respectively. Operating means is provided for the sets of disc clutches 102, 103 and 106, 107, so that when one of each of these pairs is applied the other of said pair is always released, and this operating means, as shown in Fig. 9, comprises a shifter member 110 having a shifter member 111 connected by a crank pin and crank 112 to a vertical operating shaft 113 (see Fig. 9). The shaft 113 has an operating handle 114 arranged at the top of the main base. The other set of clutches has similar operating means including a similar operating handle 115. It will thus be seen that when one or the other of the sets of clutches is applied, the shafts 104, 105, may be driven in the same direction at either a high or a low speed. Keyed to the rear ends of the parallel shafts 104, 105, respectively, are bevel gears 116 and 117 (see Fig. 5) meshing with bevel gears 118 and 119, respectively, the latter gears being fixed to horizontal relatively oppositely rotatable shafts 120 and 121 arranged on horizontal aligned axes extending transversely of the main base and suitably journaled within the latter. Fixed to and driven by these shafts 120, 121 are spur gears 122 and 123, respectively, meshing with spur gears 124 and 125, respectively, secured to the drums 7 and 8. As clearly shown in Fig. 8, the spur gear 124 is secured by screws 126 to the adjacent flange of the drum 8. The mounting and controlling structures for each drum are of the same design, and therefore the description of the mounting and control means for the drum 8 will suffice for both drums. The hub of the drum 8 is journaled on a bearing sleeve 127 supported on a stub shaft 128 mounted in a support 129 integral with the main base, and this drum is mounted to slide in an endwise direction with respect to the shaft 128. The means for so sliding the drum with respect to the shaft 128 comprises a link 130 pivotally connected at 131 to a pin secured to the inner portion of the bearing sleeve 127, and this link is in turn pivotally connected at 132 to a lever 133 pivotally mounted at 134 on the top of the main base and having a suitable operating member 135. It will thus be seen that by swinging this lever the drum 8 may move outwardly with respect to the shaft 128, thereby to bring the teeth of the gear 124 out of meshing engagement with the teeth of the gear 122. The operating means for shifting the gear 125 of the drum 7 out of mesh with the teeth of the gear 123 includes a similar operating lever 136. The means for guiding the feed cables 9 and 10 with respect to their drums comprises horizontal sheaves 140, 141 and 142 (see Figs. 1 and 2) journaled on vertical axes on the rear end of the main base, while mounted on flanges 143 integral with the sides of the skid plate 1 are horizontal guide sheaves 144 and 145.

145. Arranged on horizontal axes at the rear of the drums are vertical guide sheaves 146 and 147. The feeding cables may be extended from their drums about various guide sheaves in various manners. The drums may be rotated in winding direction in relatively opposite directions at either a high or a low speed under the control of the disc clutches of the high and low speed driving gearings, the cables being wound oppositely on their respective drums so that the latter always tend to wind in the cables.

The hydraulic power system, as shown in Fig. 13, in general comprises a pump 150 of the well known gear type suitably driven by the motor 11, a fluid reservoir tank 151 in which the pump is located, a valve box 152 containing control valves, the hydraulic pressure operated pistons and cylinders and conduits completing the hydraulic circuit. The pump, fluid tank and valve box structures are similar to those described in my copending application Ser. No. 684,707 filed August 14, 1933, and therefore a description herein of the specific structure thereof is considered unnecessary. The pump 150 is provided 25 with a master control valve 153, while the valve box 152 contains three control valves 154, 155 and 156, the valve 154 controlling the cutter blade swing cylinder 80, the valve 155 controlling the "walking" jack cylinder 25 and the valve 156 controlling the longitudinal feed cylinders 21, 21. A supply conduit 157 leads from the tank 151 at the pressure side of the pump to the valve box 152, while a return conduit 158 leads from the valve box 152 back to the tank 151 at the 35 intake side of the pump. Leading from the valve box 152 to the opposite ends of the cutter blade swing cylinder 80 are conduits 159 and 160, while leading from the valve box to the "walking" jack cylinder 25 is a conduit 161. Leading from 40 the valve box 152 to the forward ends of the feed cylinders 21 is a conduit 162, while leading from the valve box to the rear ends of the feed cylinders 21 is a conduit 163. When the master valve 153 is open to supply pressure to the supply conduit 157 and the control valve 154 is suitably operated, hydraulic pressure may be supplied to one end or the other of the cutter blade swing cylinder 80, and when pressure is supplied through conduit 159 to the rear end of the cutter 45 blade swing cylinder 80, the conduit 160 is connected through the valve box to the pressure return conduit 158, and when the conduit 160 is connected to the pressure side of the pump, the conduit 159 is connected through the valve box 50 to the return conduit 158. Pressure may be supplied through the conduit 161 to the "walking" jack cylinder 25 under the control of the valve 155, while pressure may be supplied to the feed cylinders 21, under the control of the valve 156. 55 When pressure is supplied to the forward ends of the feed cylinders 21, the conduit 162 is connected to the pressure side of the pump, while the rear ends of the feed cylinders are connected through the valve box 152 to the return conduit 158. When the rearward ends of the feed cylinders 21 are connected to the pressure side of the pump through the conduit 163, the forward ends 60 of the feed cylinders are connected to the return conduit 158 through the conduit 162. It will thus 65 be seen that hydraulic pressure may be supplied to the cutter blade swinging device, the feeding devices and the "walking" jack device under the control of independent valve means and that the parts may be hydraulically operated and 70 hydraulically locked in position.

A general summary of the operation of the coal mining machine will now be made. The machine is preferably transported over considerable distances within the mine by being carried on an ordinary mine truck which moves on the usual track rails laid in the various passages of the mine. Such a truck forms no part of the present invention. The machine may be drawn up on the truck by hooking the ends of the cables 9 and 10 to the truck, starting the motor 11 and 10 causing either of the winding drums 7 or 8 to be put into operation by moving the control levers 136 or 135, respectively. Similarly, the machine may be moved off the truck by hooking the ends of the cables 9 and 10 to an anchor jack, operating 15 the winding drums and pulling the machine toward the anchor jacks. In each case the cables are guided by the sheaves 146, 147, also by such of the sheaves 140, 141, 142, 144 and 145 as may be 20 most convenient in the particular instance.

In bringing the machine up to the face of the coal in the mine chamber, it is most convenient to use the "walking" jack device 25, 26, 27 in connection with the longitudinal feeding devices 21, 21 as previously described. The "walking" 25 jack is operated to raise the machine bodily substantially off the mine floor and the longitudinal feed cylinders 21 are then used for forward feed, extending the sub-frame or skid plate 1 attached thereto, whereupon the piston of the "walking" 30 cylinder is allowed to move upward, thus bringing the skid plate to rest on the mine floor. The longitudinal feed cylinders are then again operated and the main base 3 fed forward along the skid plate. This alternate use of the "walking" 35 and feeding cylinders to advance the machine may be repeated as often as desired, causing the machine to travel with a "walking" action rapidly over the mine floor.

When the machine is advanced as far as the 40 mine wall, the same "walking" motion may be used during the sumping cut which effects insertion of the cutter blade deep within the coal face. The skid plate 1 is first advanced as far as possible by the use of the "walking" cylinder 45 and the longitudinal feeding cylinders, whereupon the latter are set in motion to advance the main base 3 and the cutting mechanism carried by it forwardly along the skid plate 1, feeding the cutter blade into the wall of the coal, the 50 endless cutter chain having been previously set in motion by connecting the clutch of the cutter chain driving gearing. When the main base 3 has been brought completely over the skid plate 1 the latter is again advanced by operating the 55 "walking" jack, and the longitudinal feeding process again repeated. The speed of feeding in any direction is regulated by the control valve 153, thereby increasing or decreasing the amount of fluid entering the pump and hence varying the 60 rate at which the liquid will be transmitted to the various hydraulic cylinders.

With the sumping cut completed, assuming that a vertical sump has been made, as in full lines in Fig. 2, the vertical or shearing slot may now be completed by moving the control valve 154 to cause pressure fluid to enter the cutter blade swing cylinder 80 and causing the piston to be moved, and resultantly swinging downward the cutter blade. The speed of swinging movement 70 of the cutter blade may be controlled by adjusting the valve 154. The cutter blade then may be withdrawn from the slot by causing the "walking" jack and the longitudinal feed cylinders to operate in the manner previously described. 75

To cut a horizontal slot, such as is indicated in dotted lines in Fig. 1 and shown diagrammatically in Fig. 14, the cutter blade is brought into its horizontal cutting position by rotating the cutter head about its longitudinal axis with respect to the main base. The horizontal sumping cut of the cutter blade is accomplished like the vertical cut previously described by operating the "walking" cylinder and the longitudinal feed cylinders. To move the machine laterally to form a horizontal slot transversely across the coal face the winding drums 7 and 8 are used, the cables 9 and 10 therefrom being attached to anchor jacks located adjacent the ribs in the manner shown in Fig. 14. By moving the control levers 114, 115 either of the winding drums may be set in motion at any of the speeds provided by the transmission gearing or friction clutches. The winding drum 7 winds in the cable 9, while the drum 8 may turn to pay out the other cable 10. The skid plate 1 may be adjusted forwardly or rearwardly of its midposition by whatever amount is necessary to maintain the proper angle of the mining machine relative to the coal face, and this is accomplished by using the "walking" cylinder and the longitudinal feed cylinders or the longitudinal feed cylinders alone, and thereby avoids the need of using a retarding cable at the rear end of the machine, the cables 30 extending from the drums around the front guide sheaves 144, 145 laterally directly to their anchor jacks in the manner shown. To cut a bottom slot, the cutter head is rotated to bring the cutter blade into the horizontal bottom cutting position, and the machine is operated across the face in the opposite direction by the drum 8. During the shearing operation shown in Fig. 15 the cutter blade is swung upwardly with its tip end adjacent the roof by the hydraulic cylinder 80, and when the blade is in this position it may be sumped in by moving the main base forwardly with respect to the skid by the hydraulic feed cylinders 21. Thereafter the cutter blade may be swung downwardly in its plane by the swinging cylinder 80 and thereafter withdrawn from the coal face by the feed and "walking" jack cylinders 21 and 25. Obviously sumping and withdrawal can be effected by the cables 50 as well as in the manner above described.

As a result of this invention it will be noted that an improved coal mining machine of the flexibly fed, floor type is provided having relatively great universality, it being possible to operate the machine as a horizontal bottom cutter, top cutter, and shear cutter, to suit varying mining conditions. It will further be noted that the machine is of an extremely flexible character, it being possible rapidly and with facility to maneuver the machine and feed the machine during the cutting operation. Further by the provision of the power swing for the cutter blade it is possible to operate the machine as a shear cutter in an improved manner. These and other uses and advantages 60 of the improved coal mining machine will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a coal mining machine, a skid adapted to rest upon and slide in any direction over the mine floor and having longitudinal guideways, a frame guided on said skid guideways, a cutter head mounted on said frame to rotate relative thereto about a longitudinal axis, a cutter blade pivotally mounted on said cutter head, motor operated mechanism for swinging said cutter blade about its pivot with respect to the head, means for moving said frame along said skid guideways, and flexible feeding means for the machine for feeding the machine bodily over the mine floor and including a flexible feeding element adapted to be anchored at a point extraneously of the machine. 5
2. In a coal mining machine, a skid adapted to rest upon and slide in any direction over the mine floor, flexible feeding means for the skid, said skid having longitudinal guideways, a main base slidably guided on the skid guideways, means for moving said main base with respect to said skid, a cutter head mounted on said main base to rotate relative thereto about a longitudinal axis, a cutter blade pivotally mounted on said cutter head, means for swinging said cutter blade with respect to said head, and motor operated devices for actuating said base moving means and said blade swinging means. 10
3. In a coal mining machine, a skid adapted to rest upon and slide in any direction over the mine floor and having longitudinal guideways, a frame mounted on said skid guideways for reciprocation longitudinally with respect to said skid, power devices for moving said frame with respect to said skid, a cutter head mounted on said frame and rotatable relative thereto about a longitudinal axis, a cutter blade pivotally mounted on said cutter head, power devices for swinging said cutter blade with respect to said head, and power devices for feeding said machine bodily over the mine floor. 15
4. In a coal mining machine, a skid adapted to rest upon and slide in any direction over the mine floor, a main base mounted on said skid for movement longitudinally with respect thereto, a cutter head mounted on said base for rotation relative thereto about a longitudinal axis, a cutter blade pivotally mounted on said cutter head, power devices for moving said base longitudinally relative to said skid, and power devices for swinging said cutter blade with respect to said cutter head. 20
5. In a coal mining machine, a skid adapted to rest upon and slide in any direction over the mine floor, a main base mounted on said skid for movement longitudinally with respect thereto, a cutter head mounted on said base for rotation relative thereto about a longitudinal axis, a cutter blade pivotally mounted on said cutter head, power devices for swinging said cutter blade about its pivot with respect to said cutter head, means for moving said base longitudinally relative to said skid, and flexible feeding means for moving the machine bodily over the mine floor comprising relatively rotatable feeding members arranged on the base and each adapted to cooperate with flexible feeding means. 25
6. In a coal mining machine, a cutter head, a cutter blade pivotally mounted on said head to swing with respect thereto, means for locking said cutter blade in its different positions about 30

its pivot with respect to the cutter head and including a pivoted latch and spring means for urging said latch toward its locking position, means for maintaining said locking means in released position, and power devices for swinging said cutter blade with respect to said cutter head.

7. In a coal mining machine, a cutter head, a cutter blade pivotally mounted on said cutter head to swing with respect thereto, means for locking said cutter blade in its different positions about its pivot with respect to said cutter head including a pivoted latch mounted on an element swingable with the cutter blade and engageable with locking recesses on said cutter head, and separate means for maintaining said latch in its released position and releasable at will during swinging of said cutter blade.

8. In a coal mining machine, a cutter head, a cutter blade pivotally mounted on said cutter head to swing with respect thereto, means for locking said cutter blade in its different positions about its pivot with respect to said cutter head including a pivoted latch mounted on an element swingable with the cutter blade and engageable with locking recesses on said cutter head, power devices for swinging said cutter blade about its pivot with respect to the cutter head when said locking means is released, and means distinct from said blade swinging devices for maintaining said latch in its released position and releasable at will during swinging of said cutter blade.

9. In a coal mining machine, a skid adapted to rest upon and slide in any direction over the mine floor, a frame mounted on said skid for movement longitudinally with respect thereto, a cutter head mounted on said frame and rotatable with respect thereto about a longitudinal axis, a cutter blade pivotally mounted on said cutter head, means for swinging said cutter blade about its pivot relative to said cutter head, means for moving said frame longitudinally relative to said skid, and flexible feeding means for feeding the machine bodily over the mine floor including relatively rotatable feeding members arranged on the machine and each adapted to cooperate directly with a flexible feeding element.

10. In a coal mining machine, a frame, a cutter head mounted on said frame for rotation with respect thereto, a cutter blade pivotally mounted on said cutter head, and power devices including a power actuated blade swinging element mounted on said frame and connectible to said cutter blade in different predetermined positions of the cutter head about its axis for effecting cutting swinging movement of the cutter blade with respect to said cutter head, said power actuated element detachable from said cutter blade and remaining stationary, as regards rotation with said head, during head rotation.

60 11. In a coal mining machine, a frame, a cutter head mounted on said frame for rotation with respect thereto, a cutter blade pivotally mounted on said cutter head for swinging cutting movement relative thereto, and power devices connectible to said cutter blade only in certain different predetermined positions of the cutter head about its axis for effecting swinging of the cutter blade with respect to said cutter head to effect cutting and including a power cylinder mounted on said frame and operatively connected to said cutter blade.

70 12. In a coal mining machine, a frame, a cutter head mounted on said frame for rotation with respect thereto, a cutter blade pivotally

mounted on said cutter head for swinging cutting movement relative thereto, and power devices connectible to said cutter blade only in certain different predetermined positions of the cutter head about its axis for effecting cutting swinging movement of the cutter blade with respect to said cutter head and including a power cylinder mounted on said frame and relative to which said head is rotatable and which is operatively connected by detachable connections to said cutter blade, said connections between said power cylinder and said cutter blade being detached from the latter during rotation of said cutter head.

13. In a coal mining machine, a support, a cutter head mounted on said support and rotatable with respect thereto about a longitudinal axis, a cutter blade pivotally mounted on said cutter head, said cutter head rotatable to move said cutter blade into vertical cutting positions at either side of the head axis, and power devices including a power actuated blade swinging element mounted on said support connectible to the cutter blade in either of aforesaid vertical cutting positions for swinging said cutter blade in its cutting planes with respect to said cutter head in either vertical cutting position, said power actuated element detachable from said cutter blade and remaining stationary, as regards rotation with said head, during head rotation.

14. In a coal mining machine, a support, a cutter head mounted on said support and rotatable with respect thereto, a cutter blade pivotally mounted on said saw head for swinging cutting movement relative thereto, said saw head being rotatable to move said cutter blade into vertical cutting positions at either side of the head axis, and power devices connectible to the cutter blade in either of the aforesaid vertical cutting positions for swinging said cutter blade with respect to said cutter head in either vertical cutting position to effect cutting, and including a power cylinder mounted on said support and operative connections between said power cylinder and the cutter blade respectively alternatively usable in said different vertical cutting positions of said blade.

15. In a coal mining machine, a support, a cutter head mounted on said support and rotatable with respect thereto, a cutter blade pivotally mounted on said saw head for swinging cutting movement relative thereto, said head being rotatable to move said cutter blade into vertical cutting positions at either side of the head axis, and power devices for swinging said cutter blade with respect to said head in either of the aforesaid vertical cutting positions to effect cutting comprising a shaft journaled on said support on a horizontal axis extending transversely of said support, power connections on either end of said shaft and power devices for rotating said shaft, said cutter blade being connectible with one of said power connections when in one of the aforesaid vertical cutting positions and connectible with the other power connection when in said other vertical cutting position.

65 16. In a coal mining machine, a skid adapted to rest upon and slide in any direction over the mine floor, coal cutting devices carried by said skid, power devices for moving said coal cutting devices longitudinally with respect to said skid, power devices for substantially relieving the weight of said cutting devices from said skid comprising a power jack arranged midway between the sides of said skid and engageable with the

mine floor, said first mentioned power devices being operative, when the weight of the cutting devices is substantially relieved from the skid, to move said skid longitudinally with respect to said coal cutting devices.

17. In a coal mining machine, a skid adapted to rest upon and slide in any direction over the mine floor, coal cutting devices carried by said skid, power devices for moving said coal cutting devices longitudinally with respect to said skid, power devices for substantially relieving the weight of said cutting devices from said skid comprising a power jack arranged midway between the sides of said skid and engageable with the mine floor, said first mentioned power devices being operative, when the weight of the cutting devices is substantially relieved from the skid, to move said skid longitudinally with respect to said coal cutting devices, said skid having a centrally located longitudinally extending slot through which said jack projects into engagement with the mine floor, said slot permitting longitudinal movement of said skid with respect to said jack.

18. In a coal mining machine, a support, a cutter head rotatably mounted on said support, a cutter blade pivotally mounted on said cutter head, said cutter head being rotatable to move said cutter blade into different vertical cutting positions, and power devices on said support and connectible to said cutter blade for swinging said cutter blade with respect to said head into either of the aforesaid vertical cutting positions, said cutter blade having a plurality of points widely spaced, alternatively usable of connection with said power devices for the application of swinging forces thereto.

19. In a coal mining machine, a support, a cutter head rotatably mounted on said support, a cutter blade pivotally mounted on said cutter head, said cutter head being rotatable to move said cutter blade into vertical cutting positions, and power devices on said support and connectible to said cutter blade for swinging said cutter blade with respect to said head into either of the aforesaid vertical cutting positions, said cutter blade having a plurality of widely spaced points of connection with said power devices, and said power devices being connectible to one of said points of connection with said cutter blade when the latter is in one vertical cutting position and with the other of said points of connection when said blade is in said other vertical cutting position.

20. In a coal mining machine, a support, a cutter head rotatably mounted on said support, a cutter blade pivotally mounted on said cutter head, said cutter head being rotatable to move said cutter blade into vertical cutting positions, and power devices on said support and connectible to said cutter blade for swinging said cutter blade with respect to said head into either of the aforesaid vertical cutting positions, said cutter blade having a plurality of widely spaced points of connection with said power devices, and said power devices being connectible to one of said points of connection with said cutter blade when the latter is in one vertical cutting position and with the other of said points of connection when said blade is in said other vertical cutting position, said power devices including a hydraulic cylinder on said support and a piston reciproable in said cylinder.

21. In a mining machine, a base having longitudinal guideways, propelling means for said base,

a frame slidably guided on said base guideways, means for moving said frame longitudinally with respect to said base guideways, a cutter head mounted on said frame to rotate relative thereto about a longitudinal axis, a kerf cutter pivotally mounted on said cutter head, means for swinging said kerf cutter with respect to said head, and motor operated means for actuating said frame moving means and said kerf cutter swinging means.

22. In a mining machine, a base having longitudinal guideways, a frame mounted on said base guideways for reciprocation longitudinally with respect to said base, power devices for reciprocating said frame with respect to said base, a cutter head mounted on said frame and rotatable relative thereto about a longitudinal axis, a kerf cutter pivotally mounted on said cutter head, power devices for swinging said kerf cutter with respect to said head, and power devices for bodily feeding the machine.

23. In a mining machine, a frame, a cutter head mounted on said frame for rotation with respect thereto, a kerf cutter pivotally mounted on said cutter head to swing in its cutting planes relative thereto, and power devices connectible to said kerf cutter in different predetermined positions of the cutter head about its axis for effecting swinging of the kerf cutter with respect to said cutter head and including a motor mounted on said support and cooperating relatively movable swinging elements relatively actuated by said motor and operatively connected to said kerf cutter, said cutter swinging elements disconnected wholly from said cutter and remaining stationary with said frame during head rotation.

24. In a mining machine, a frame, a cutter head mounted on said frame for rotation with respect thereto, a kerf cutter pivotally mounted on said cutter head for cutting swinging movement relative thereto, and power devices connectible to said kerf cutter in different predetermined positions of the cutter head about its axis for effecting swinging of the kerf cutter with respect to said cutter head and including a motor mounted on said support and operatively connected to said kerf cutter, said connections between said motor and said kerf cutter being detached from the latter during rotation of said cutter head and connected to said kerf cutter in aforesaid predetermined positions of said cutter head.

25. In a mining machine, a support, a cutter head mounted on said support and rotatable with respect thereto, a kerf cutter pivotally mounted on said cutter head for cutting swinging movement relative thereto, said cutter head being rotatable to move said kerf cutter into vertical shearing positions at either side of the head axis, and power devices connectible to said kerf cutter in either of aforesaid vertical shearing positions for swinging said kerf cutter with respect to said cutter head in either vertical shearing position and including a motor mounted on said support, and operative connections between said motor and said kerf cutter, said connections including relatively movable cutter swinging elements relatively actuated by said motor and wholly disconnected from said cutter and remaining stationary with said frame during head rotation.

26. In a mining machine, a support, a cutter head mounted on said support and rotatable with respect thereto, a kerf cutter pivotally mounted on said cutter head for cutting swinging move-

ment relative thereto, said head being rotatable to move said kerf cutter into vertical shearing positions at either side of the head axis, and power devices for swinging said kerf cutter with respect to said head in either of aforesaid vertical shearing positions comprising transmission connections journaled on said support, spaced power connections actuated by said transmission connections, one power connection located at each side of the support, and power devices for driving said transmission connections, said kerf cutter being connectible with one of said power connections when in one of the aforesaid vertical shearing positions and connectible with the other power connection when in said other vertical shearing position.

27. In a mining machine, a skid adapted to rest upon a slide in any direction over the mine floor and having longitudinal guideways, a frame mounted on said skid for movement longitudinally along said guideways, a vertical shear cutter adjustable into parallel vertical cutting positions with respect to said frame and pivotally mounted on said frame to swing in vertical planes with respect thereto in any vertical cutting position about a horizontal axis located at the forward end of said frame, motor operated means for moving said frame longitudinally of said skid, motor operated means for swinging said vertical shear cutter about its pivot in any vertical cutting position, and motor operated means for actuating said shear cutter.

28. In a mining machine, a skid adapted to rest upon and slide in any direction over the mine floor and having longitudinal guideways, a frame mounted on said skid for movement longitudinally along said guideways, a vertical shear cutter adjustable into parallel vertical cutting positions with respect to said frame and pivotally mounted on said frame to swing in vertical planes with respect thereto in any vertical cutting position about a horizontal axis located at the forward end of said frame, motor operated means for moving said frame longitudinally of said skid, motor operated means for swinging said vertical shear cutter about its pivot in any vertical cutting position, motor operated means for actuating said shear cutter, and means for moving the skid bodily laterally over the mine floor to locate the machine in different vertical shearing positions with respect to the coal face.

29. In a mining machine, a skid adapted to rest upon and slide in any direction over the mine floor and having longitudinal guideways, a frame mounted on said skid for movement longitudinally along said guideways, a cutter head mounted on the forward end of said frame to rotate relative thereto about an axis extending longitudinally of the machine, a vertical shear cutter pivotally mounted on said cutter head to swing relative thereto about a horizontal axis and rotatable with said cutter head into different vertical shearing positions at opposite sides of the head axis, motor operated means for moving said frame along said skid guideways, motor operated means for swinging said kerf cutter about its pivot relative to the cutter head in either of aforesaid vertical cutting positions, and motor operated means for actuating said kerf cutter in either adjusted position thereof.

30. In a mining machine, a skid adapted to rest upon and slide in any direction over the mine floor and having longitudinal guideways, a frame mounted on said skid for movement longitudinally along said guideways, a cutter head mounted

on the forward end of said frame to rotate relative thereto about an axis extending longitudinally of the machine, a vertical shear cutter pivotally mounted on said cutter head to swing relative thereto about a horizontal axis and rotatable with said cutter head into different vertical shearing positions at opposite sides of the head axis, motor operated means for moving said frame along said skid guideways, motor operated means for swinging said kerf cutter about its pivot relative to the cutter head in either of aforesaid vertical cutting positions, motor operated means for actuating said kerf cutter in either adjusted position thereof, and means for feeding the skid bodily laterally over the mine floor to move bodily the machine into different vertical cutting positions relative to the coal face.

31. In a mining machine, a base having longitudinal guideways, a frame mounted on said base guideways to slide longitudinally therealong, a cutter head mounted on said frame for rotation about a horizontal axis extending longitudinally of said frame, a kerf cutter pivotally mounted on said rotatable cutter head to swing relative thereto, hydraulically operated means for moving said base longitudinally along said base guideways, hydraulically operated means for swinging said kerf cutter relative to said cutter head, a motor driven pump on said sliding frame, and means under manual control for supplying liquid under pressure from said pump to said hydraulically operated means.

32. In a mining machine, a base having longitudinal guideways, a frame mounted on said base guideways to slide longitudinally therealong, a cutter head mounted on said frame for rotation about a horizontal axis extending longitudinally of said frame, a kerf cutter pivotally mounted on said rotatable cutter head to swing relative thereto, a pair of hydraulic cylinders containing reciprocable pistons for moving said frame longitudinally along the base guideways, a hydraulic cylinder containing a reciprocable piston for swinging said kerf cutter relative to said cutter head, a motor driven pump on said sliding frame, and means under manual control for supplying liquid under pressure from said pump to said hydraulic cylinders.

33. In a coal mining machine, a support, a kerf cutter pivotally mounted on said support to swing with respect thereto, means for locking said kerf cutter in its different positions about its pivot with respect to said support including a latch pivoted to swing about an axis at right angles to the pivotal axis of the kerf cutter and mounted on an element swingable with the kerf cutter, said latch engageable with locking recesses on said support, and separate means engageable with said latch for maintaining the latter in its released position.

34. In a coal mining machine, a support, a kerf cutter pivotally mounted on said support to swing with respect thereto, means for locking said kerf cutter in its different positions about its pivot with respect to said support including a latch pivoted to swing about an axis at right angles to the pivotal axis of the kerf cutter and mounted on an element swingable with the kerf cutter, said latch engageable with locking recesses on said support, means engageable with said latch for maintaining the latter in its released position, and power devices for swinging said kerf cutter about its pivot with respect to said support when said latch is released.

CERTIFICATE OF CORRECTION.

Patent No. 2,089,964.

August 17, 1937.

JOSEPH F. JOY.

It is hereby certified that error appears in the printed specification of the above numbered patent requiring correction as follows: Page 1, second column, line 14, strike out the word "showing" and insert the same before "the" first occurrence, in line 15; page 6, second column, lines 34, 35 and 51, claims 14 and 15 respectively, for "saw" read cutter; page 7, first column, lines 34 and 35, claim 18, strike out "widely spaced, alternatively usable" and insert the same before "points" in line 34, same claim; line 64, claim 20, strike out "widely"; page 8, first column, line 18, claim 27, for the article "a" read and; and that the said Letters Patent should be read with these corrections therein that the same may conform to the record of the case in the Patent Office.

Signed and sealed this 7th day of December, A. D. 1937.

Henry Van Arsdale,
Acting Commissioner of Patents.
